FREQUENCY CONTROLLED MECHANISM

Werner Koenig, Zug, Switzerland, assignor to
 Landis & Gyr, A.-G., Zug, Switzerland, a corporation of Switzerland

Application January 13, 1931, Serial No. 508,475
 In Switzerland January 15, 1930

4 Claims. (Cl. 175—338)

The present invention relates to frequency controlled mechanism and more particularly to a novel and useful frequency controlled mechanism in which a rotating member is controlled and actuated by a frequency responsive member.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serve to explain the principles of the invention.

Of the drawing:

Figure 1 is a front elevation of one illustrative embodiment of the present invention, certain parts being omitted;

25 Figure 2 is a plan of the embodiment shown in Figure 1, certain parts being broken away;

Figure 3 is a fragmentary and diagrammatic detail elevation of the embodiment of Figure 1;

30 Figure 4 is a diagrammatic view illustrating a modified embodiment of the present invention; and

Figure 5 shows diagrammatically a special arrangement of the magnet core which may be employed in connection with the present invention.

The present invention has for its object the provision of a frequency controlled mechanism, suitable for use in connection with the operation of switching mechanism, registers or recording mechanism. A further object is the provision of such a mechanism which is efficient and reliable in its operation and at the same time simple and of relatively inexpensive construction. Still another object is the provision of such a mechanism in which the parts need not be initially adjusted, and need not be adjusted from time to time to compensate for wear.

In accordance with the present invention, a resonant reed is provided, adapted to vibrate when subjected to a driving force of the proper frequency, and cooperates with a rotating member to intermittently rotate the member. As embodied, the rotating member is normally held

only by resonant vibration of the vibratory member.

It will be understood that the foregoing general description and the following detailed description as well, are exemplary and explanatory of the invention, but are not restrictive thereof.

Referring now in detail to the present preferred and illustrative embodiment of the present invention, a resonant spring member or reed 10 of resilient magnetic material is securely 10 mounted in a frame by means of the cross members 11, and its free end is positioned between the pole pieces 12 of a driving electromagnet 13, which may be supplied with a fluctuating or alternating electrical current of a predetermined 15 frequency through the mains 14.

Cooperating with the resonant reed 10 is a rotatable member adapted to be rotated by vibration of the reed, but normally held against rotation and released only by vibration of the 20 reed at its resonant frequency. As embodied, a shaft 15 is rotatably journaled in the side plates 16 of the mechanism and on shaft 15 is fixed a ratchet wheel 17 provided with a plurality of teeth 18. Ratchet wheel 17 preferably 25 lies to one side of and in a plane parallel to the reed 10 and is closely adjacent thereto, as shown in Figure 2.

For normally preventing rotation of the shaft 15, which may be connected with switching or 30 other mechanism, an elongated, pivoted pawl 19 is provided above reed 10 and is supported by pivot pin 20 as well as by the downwardly projecting nose 21 which rests on the reed 10 near its free and vibrating end. At one side, pawl 19 35 is provided with a pin 22 which engages with the teeth 18 of ratchet 17. Pawl 19 and its pin 22 are released from the teeth of ratchet 17 by resonant vibration of the reed 10, the pawl being lifted sufficiently by the vibration. As pawl 19 is 40 lifted, ratchet 17 is rotated, as will be more fully described, and thereafter pin 22 rides on the peripheral face of the ratchet until it comes in engagement with the next tooth 18.

For rotating the shaft 15 and ratchet 17, a thin 45 disc 25 is fixed on the shaft and rotates therewith, and is engaged at its periphery by means of a small grooved roller or disc 26, which is very loosely and rotatably mounted on a small shaft 27 carried between the ends of spring 28. Roller 26 50 is held by shaft 27 and gravity in engagement with the periphery of the disc 25 and rolls thereover.

Spring 28 is slotted throughout substantially all its length and is mounted on a weighted segment 29 which is freely rotatable with respect to shaft 55

15. For rotating disc 25 as reed 10 vibrates, a small, light plate 30 is provided and is mounted on reed 10 extending to one side thereof and so positioned that roller 26 can be wedged between the plate 30 and disc 25. Plate 30 is preferably 5 downwardly inclined at slightly less than a right angle to a line passing through shafts 15 and 27 and as reed 10 is vibrated, plate 30 is similarly vibrated causing a rapid intermittent rotation of disc 25 and roller 26 in the directions shown by 10 the arrows.

In operation, reed 10 is vibrated by the current flowing through electromagnet 13, and when this is in resonance with the reed 10, reed 10 lifts pawl 19 sufficiently to position pin 22 on the periphery 15 of ratchet 17. At the same time, plate 30 is raised while roller 26 is wedged between plate 30 and disc 25, thereby causing disc 25 and roller 26 to be moved clockwise about shaft 15 as an axis. On 20 downward movement of plate 30, disc 25 tends to remain stationary, roller 26 is released from its tight engagement with disc 25 and plate 30 and is pulled down and follows plate 30 by virtue of the weighted segment 29. The action is then 25 repeated and continues so long as the predetermined frequency is applied to the electromagnet 13.

In accordance with a modified embodiment of the invention as shown in Figure 4 of the drawing, a resonant reed 10 is rigidly mounted in a cross frame member 11 and has its free end positioned between the pole pieces 12 of a driving 30 magnet. Reed 10 is associated with a rotatable shaft 35, to be driven and controlled by vibration of the reed, and shaft 35 carries a notched disc 36 which together with pin 22 carried by the pivoted pawl 19, serves normally to prevent rotation 35 of shaft 35. Pawl 19 is provided at its free end, with a downwardly extending nose 21 which rests on the reed 10 so that pawl 19 is raised releasing disc 36 on resonant vibration of reed 10.

Shaft 35 is rotatable in the bearings 37 and has a limited degree of horizontal movement, being 40 pressed toward the free end of reed 10 by pivoted lever 38 and spring 39. For driving the shaft, in the direction of the arrow, reed 10 is provided with a laterally extending plate 40 and a smooth disc 41 is fixed on shaft 35 so that it is pressed against the plate 40 by spring 39. On vibration of the reed 10, plate 40 is similarly vibrated and contacts with the periphery of the disc 41 on its 45 downward movement.

On its upward movement, plate 40 is released from contact with the disc 41, due to the smaller mass and faster movement of the plate 40 under 50

influence of reed 10, than the lateral movement of disc 41 under spring 39.

Resonant vibration of the reed 10, first lifts pin 22 out of engagement with the notch on disc 41, and at the same time slightly advances the disc 41 to move the notch out of position to be engaged by the pin 22. On further vibration of the reed, plate 40 intermittently advances the disc 41 and shaft 35 until the pin 22 again drops in one of the notches. 5

Figure 5 of the drawing diagrammatically illustrates the present preferred arrangement of the pole pieces of the magnet in connection with a plurality of reeds 10. As shown, the pole pieces 45 overlap each other, and between them are positioned the free and vibratable ends of the resonant reeds 10. 10

The invention in its broader aspects is not limited to the specific mechanisms shown and described but departures may be made therefrom within the scope of the accompanying claims 20 without departing from the principles of the invention and without sacrificing its chief advantages. 25

What I claim is:—

1. Frequency controlled mechanism including in combination a vibrating member, a rotatable member and a roller loosely mounted on a shaft to be wedged between the vibrating member and rotatable member to drive the rotatable member 30 from the vibrating member.

2. Frequency controlled mechanism including in combination a vibrating member, a rotatable member and a roller loosely mounted on an oscillatable arm to be moved by gravity between the 35 vibrating and rotatable member.

3. Frequency controlled mechanism including in combination a vibrating member, a rotatable member, a roller mounted independently of said members and adapted to be wedged by gravity 40 between the vibrating and rotatable members, and means for releasing the wedging action on movement of the vibratable member in one direction.

4. Frequency controlled mechanism including 45 in combination a rotatable disc, a vibratable reed, means for vibrating the reed, a roller mounted independently of and between the disc and reed and wedged against the disc by movement of the reed in one direction, and means normally preventing rotation of the disc and releasing the disc 50 only on resonant vibration of the reed.

WERNER KOENIG.
